(57) **CLAIM**

The ornamental design for a street clock, as shown and described.

DESCRIPTION

FIG. 1—is a right perspective view of a street clock showing our new design;

FIG. 2—is a front elevational view thereof;

FIG. 3—is a rear elevational view thereof;

FIG. 4—is a top plan view thereof;

FIG. 5—is a bottom plan view thereof;

FIG. 6—is a right side elevational view thereof; and,

FIG. 7—is a left side elevational view thereof.

The cross-shaped elements in FIGS. 5 through 7 depicted by broken lines have been shown for the purpose of illustrating portions of the street clock that form no part of the claimed design.

The broken lines in FIG. 5 represent an unclaimed boundary, the area within which forms no part of the claimed design.
